WINDOW STOOL AIR OUTLET

Jerold H. Van Alsburg, Holland, Mich., assignor
to Hart & Cooley Manufacturing Company,
Holland, Mich., a corporation of Delaware

Application August 12, 1946, Serial No. 689,993.

4 Claims. (Cl. 98—90)

1

This invention relates to a window air outlet and is for the delivery of heated air in rooms at the bottom of surfaces which are directly affected by atmosphere of low temperature at its outside, which has the effect of lowering the temperature at the inside thereof. With my invention, heated air is supplied to rise alongside the inner side of said temperature affected surface to minimize or balance the effect produced by the outer cold atmosphere.

One place where this very commonly occurs is in connection with windows in housings or buildings. At the colder times of the year the air in the room adjacent the windows becomes considerably cooled. The cooled air drops by gravity to the floor of the room and detrimentally affects its temperature conditions. With my invention, warm air, for example, coming by forced pressure from a furnace, is delivered at the lower end of the window and rises at the inner side thereof to balance or more than balance the extraction of heat which passes through the glass of the window to the outside.

It is an object and purpose of the present invention to provide a very practical, simply made, easily installed and economically manufactured outlet for a supply of warm air to be located at the inner side of the lower sash of a window at the inner portion of the window frame sill for the delivery of heated air for such upward circulation. In many cases, such air will be supplied between the window and curtains or drapes within the room, and will pass upwardly to mix with the cold air between the curtains and window, eliminating a downward draft and circulation of air from the inner side of the window to the floor and thence into the room space.

An understanding of the invention may be had from the following description, taken in connection with the accompanying drawings, in which,

Fig. 1 is a transverse vertical section through the air outlet of my invention.

Fig. 2 is a fragmentary enlarged like section, illustrating the air outlet structure and its window and wall attachment in enlarged detail.

Fig. 3 is a fragmentary plan view of said air outlet structure.

Fig. 4 is a similar under plan view thereof.

Like references characters refer to like parts in the different figures of the drawings.

As shown in Fig. 1, a window may be located in a side wall 1 of a housing, building or the like, the window frame lower sill being indicated at 2, and with sliding window sashes 3 of conventional structure. The window may be of any of the con-

2

ventional forms and the detail of structure thereof is not important in connection with the present invention. The air outlet structure of my invention is to be located at the bottom of the window within the sill 2 and inside the lower portion of the lower sash 3, as shown in Fig. 1.

In the construction of the air outlet, a warm air receiving housing is provided, made from sheet metal, having a horizontal upper side 4 which, at its outer portion, is bent to extend downwardly in a substantially vertical plane as at 5, terminating in an outwardly extending flange 6 which lies against the upper side of the sill 2 and against the upper side of which the lower rail of the lower sash 3 is brought when the window is closed. At its forward or inwardly extending portion, the metal plate is curved downwardly substantially into semicircular form as at 7.

The top 4 of the housing may be provided with a plurality of air outlet openings 8, shown as in alignment and spaced short distances from each other but, evidently, they may be otherwise arranged in accordance with any desired pattern. The under side of the housing comprises a horizontal plate 9 spaced from the top 4, which extends inwardly toward the free edges of the curved inner end 7 described. The plate 4 at each end at its inner portion is extended, as shown at 4a, lying within the window frame, while the shorter section of the top 4 lies between the opposed sides of the window frame. The lower side or bottom 9 of the housing at each end is extended outwardly and at each end has fingers 10 which overlap at free edge portions of the curved section 7 and may be permanently connected therewith, leaving an elongated slot 11 between the free lower edge of the section 7 and the inner edge of the bottom 9.

At its outer portion the bottom plate 9 is provided with an elongated inlet opening 12 surrounded by downwardly extending sides and ends 13, as best shown in Fig. 2, and above the outermost side of which the metal is extended upwardly in a section 14 lying within and against the section 5 previously described, and permanently connected therewith. It is to be understood that the ends of this housing are closed by sheet metal members so that there is a closed housing having an air inlet at 12 and outlets at 50 the openings 8 and slot 11. A flue 15 located within the wall 1, at its upper end enters the surrounding downwardly extending wall 13 around the inlet opening 12. Such flue is connected with the air circulation circuit which carries heated air from a furnace, for example, and

which air preferably will be forcibly moved by a fan within the furnace or any other equivalent air pressure circulating means.

With the structure installed as described, the air forced upwardly through the flue 15, as arrow indicated, enters the housing through the inlet at 12 and leaves it through the outlet openings 8 and the slot 11. It is apparent that either the openings at 8 or the slot at 11 may be eliminated so that the air will leave the housing only through the outlet remaining. Heated air rises because of its lesser weight than cold air, and will pass upwardly at the inside of the window to meet the colder air from which heat has passed through the glass of the window to the outside colder atmosphere. The air passing upwardly through the outlet openings at 8 will mingle with that closest to the window glass, and that passing through the outlet slot 11, will pass around the curved outer section 7 of the housing and thence upwardly for intermingling with air farther away from the window. In cases, where curtains are suspended from above the upper ends of the window to below their lower sides, the intermixed colder air and heated air take place largely between the window and curtains. In any case, there will be eliminated and avoided a delivery of air at a lower temperature to the room which, when it occurs, results in lower temperature currents of air at and above the floor of the room. Such undesirable effect is eliminated with my invention. The structure described is practical and economical to make and is readily installed.

The invention is defined in the appended claims and is to be considered comprehensive of all forms of structure coming within their scope.

I claim:

1. In a structure as described, an elongated housing having a substantially horizontal top of sheet metal, a vertical side section extending from said horizontal top at its outer edge for a distance and an outwardly extending flange extending from said section, said top at its opposite longitudinal edge being curved downwardly and back upon itself to provide an opposite side for the housing, vertical ends, a substantially horizontal bottom having an air entrance opening and downwardly extending walls surrounding said opening, said bottom at both ends thereof having forwardly extending fingers secured to said curved side of the housing with an air outlet opening between the adjacent edges of said bottom and side members and disposed between said fingers, said wall around the air inlet opening being adapted to have connection with a vertically disposed air carrying flue.

2. A window heated air receiving and delivering structure comprising, a housing of sheet metal having spaced horizontal top and bottom, said top and bottom at the outer portions thereof having a length to extend between the inner sides of the vertical sides of a window frame and at their inner portions increased in length to extend beyond the inner sides of said window frame sides, vertical end closures for the housing, a vertical outer side having an outwardly extending flange adjacent the upper side of a window sill, and an inner side curved substantially in the arc of a circle from the top to said bottom, said bottom at its intermediate portion and at its inner edge terminating a short distance from the free edge of said curved side of the housing, and said bottom at its inner side portions having fingers extending to and overlapping and connected with said curved side of the housing, and said bottom adjacent the other side of the housing having an air entrance opening surrounded by downwardly extending flanges, within which the upper end of a vertical air carrying flue is adapted to be inserted.

3. A construction as defined in claim 2, said top between the sides of the housing having a plurality of spaced openings therethrough in alignment with each other lengthwise of the top.

4. In a structure as described, an elongated housing having spaced horizontal top and bottom, vertical ends and generally vertical sides, said bottom having an air outlet slot lengthwise thereof adjacent one side and an air entrance opening adjacent its other side, said bottom having downwardly extending flanges surrounding said entrance opening, and a vertical air flue having its upper end portion telescopically received within said flanges, said top of said housing having a plurality of spaced air outlet openings therethrough.
